LOCKING DEVICE

Richard H. Davis, 280 Richton, Highland Park, Mich.

Filed Nov. 6, 1959, Ser. No. 851,363

3 Claims. (Cl. 70—93)

This invention relates to locking devices for locking panel doors and the like.

Heretofore, it has been a problem to provide panel doors of the swingable and slide types with reliable locking means. Numerous locking devices for panel doors have been proposed. However, all can be pried open or apart by means of jimmies, crowbars and the like.

An object of this invention is to provide a locking device, and in particular a locking device for doors and the like, which cannot readily be pried apart and open by jimmies and other burglary tools.

Other objects of the invention will become more apparent by reference to the following detailed description taken in conjunction with the accompanying drawing in which:

FIG. 1 is an elevational view of the lock side of adjacent end portions of a pair of door panels incorporating a preferred embodiment of the locking device of this invention.

FIG. 2 is a cross sectional view of the door panels and of the lock of FIG. 1 as seen substantially in the plane of line 2—2 thereon.

FIG. 3 is a cross sectional view of a portion of the lock of FIG. 2 taken on the line 3—3 thereon.

Referring now to the drawing wherein like reference characters refer to like and corresponding parts throughout the several views, the particular embodiment of the invention disclosed for illustrative purposes is shown by FIG. 1 in combination with the adjacent end portions of two panel doors 10 and 12, which may be either of the slideable or swingable type. Each door panel 10 and 12 in a corresponding region of the adjacent ends is provided with a hole 14 therethrough. The locking device embodiment, indicated generally by the reference numeral 16, is mounted on the lock side of the door panels 10 and 12 with the aid of these holes 14.

The locking device 16 comprises the combination of first pin means 18, fastener means 20, second pin means 22, lock fastener means 24 and latch chain means 26.

The first pin means 18 is preferably in the form of a bolt having a head 28 and a shank 30. Preferably the shank 30 from the head to the end region thereof has a smooth outside surface portion 301 and in said end region to the end a threaded portion 302. The shank 30 is insertable in sliding fit through the hole 14 of the panel door 10. The head 28 should be on the lock side of the panel door 10 and the threaded portion 302 of the shank 30 should extend outwardly from the opposite side of the panel door 10 in order to receive the fastener means 20.

The fastener means 20 in the embodiment shown are a pair of nuts 201 and 202, which are threaded for engagement in tandem with the threaded shank portion 302 of the bolt 18.

The second pin means 22 is in the form of an unthreaded bolt or pin having a head 32 and a shank 34 having a smooth outside surface. In the region of the end of the shank 34 the pin 22 is adapted for receiving the lock fastener means 24. The shank 34 is insertable in sliding fit through the hole 14 of the panel door 12. In this regard, the end of the shank 34 should extend outwardly from the lock side of the panel door 12 and the head 32 should be on the opposite side of the panel door 12.

The lock fastener means 24 comprises a peg 36 and a lock assembly 42. The peg 36 is intended to be inserted

2

through a transverse passageway through the shank 34 of the pin 22 in the region of the end thereof. Accordingly, the shank 34 of the pin 22 is provided with a transverse hole 341 therethrough in the region of the end thereof for receiving in sliding fit the peg 36. The said peg 36 comprises a head 38 and a smooth shank 40. The head 38 of the peg 36 is larger than the transverse hole 341 therethrough. In the region of the end of the shank 40 of the peg 36, there is provided an annular recess 401 for engagement by the barrel lock assembly 42.

The barrel lock assembly 42 includes a barrel casing 44 and a cylinder lock 46. The casing 44 has a passageway 441 with an opening at one end thereof for receiving in sliding fit the shank 40 of the peg 36. It also has a cylinder lock chamber 442 for receiving the cylinder lock 46 and a cam chamber 443 interconnecting the passageway 441 and the cylinder lock chamber 442 for accommodating a cylinder lock cam. The cylinder lock 46 is of a conventional type. Within the cylinder lock 46 there are conventional tumblers and the like, not shown, which prevent an inner revolving plug 461 thereof from rotating until the tumblers are engaged by the stem of an appropriate key 48 inserted into the key slot of the revolving plug. Mounted on the revolving plug 461 is a cam 462 which, when the lock 42 is in locked condition and the shank 40 of the peg 36 is in position in the passageway 441, is disposed or seated in the annular recess 401 of the said peg 36. When the said lock 42 is in its unlocked condition, the said cam 462 is out of engagement with the annular recess 401 of the peg 36. To hold the cylinder lock 46 in position in the barrel casing 44, a transverse threaded bore 444 is provided through the casing 44 to the cylinder chamber 442, and a threaded set screw 50 is provided in the said casing 44 which engages the cylinder lock 46 as shown. The portion of the bore 444 between the outside of the casing 44 and the top of the set screw 50 is plugged with a plug 52 of lead, solder and the like.

The latch chain 26 comprises a number of intermediate chain links 261 and end links 262 and 263. The end links 262 and 263 are mounted respectively on the shanks 30 and 34 of the pins 18 and 22 in sliding fit on the lock side of the panel doors 10 and 12. With the pins 18 and 22 mounted in the holes 14 of the panel doors 10 and 12 and the end links 262 and 263 mounted as stated, the latch chain 26 preferably just spans the gap between the pins 18 and 22 with perhaps a small amount of slack. The end link 262 is prevented from slipping off the shank 30 of the first pin 18 by the head 28 while the end link 263 is kept in place on the shank 34 of the second pin 22 by the lock fastener means 24.

It is required in the more specific aspects of this invention that with the first pin 18 extending outwardly from the panel door 10 as far as it can go with the nuts 201 and 202 in place the distance between the head 28 thereof and the nearest surface of the panel door 10 be at least, and preferably greater than, the jimmy distance. "Jimmy distance" as used herein refers to the straight line distance from the prying end of a jimmy or the like to the most distant fulcrum point thereof (that part of the surface thereof which normally bears against a stationary surface for leverage) in which the prying action of the jimmy or the like is effective.

It is further required in the more specific aspects of this invention that with the second pin 22 fully extended outwardly from the panel door 12 as far as it can go as determined by the head 32 the distance between the lock fastener means 24, particularly the barrel casing 44, and the nearest surface of the panel door 12 be at least, and preferably greater than, the jimmy distance. Furthermore, with the head 38 of the peg 36 abutting the shank 34 of the second pin 22 the shortest distance between the

shank 34 and the barrel casing 44 should be at least, and preferably greater than, the jimmy distance.

For maximum protection it is recommended that annular washers 54 also be employed on each side of each panel door 10 and 12 about the holes 14. Preferably the inside diameter of the washers 54 should be at least sufficient to accommodate in sliding fit the respective shanks 30 and 34 of the pins 18 and 22. Moreover, it is preferred that the outside diameter of the washers 54 be sufficiently large so that each washer 54 covers a wide area. When washers 54 are used, the jimmy distance is measured from the outer surface thereof to the head 28, lock fastener means 24, etc.

Materials of construction used in the locking device 16 are conventional. Generally, it is preferred too that the pins 18 and 22, peg 36, latch chain 26, barrel casing 44, cam 462, revolving plug 461, nuts 201 and 202, and washers 54 be of hardened and toughened metal, such as hard or hardened steel.

With the locking device 16 in open condition such that the door panels 10 and 12 are in unlatched condition, the end link 262 of the latch chain 26 will be off the pin shank 34. Usually, to prevent misplacement or loss of the lock fastener means 24, it is best to have the same in position on the pin shank 34 and in locked condition. However, this is not necessary if there is a friction fit of the shank 34 of the pin 22 in the bore 14 of the door panel 12.

To lock the door panels 10 and 12 with the locking device 16 just described, the key 48 for the cylinder lock 46 is inserted into the key slot of the revolving plug 461, turned and the barrel lock assembly 42 removed from the end of the peg 36. The peg 36 is removed from the end of the second pin 22 and the end link 262 of the latch chain 26 placed on the second pin shank 34. The peg 36 is then inserted through the peg hole 341 and the barrel lock assembly 42 placed into position on the peg 36. The key 48 is then turned whereby the cam 462 becomes positioned in or seats in the annular recess 401 of the peg shank 40. The key 48 is then removed from the key slot. The door panels 10 and 12 are now locked. Moreover, they are locked against burglars or others forcing the locking device.

An advantage of the locking device just described is its inherent simplicity and uncomplicated structure, and no great skill is needed to use the locking device.

A most important advantage of the locking device is that the pertinent parts thereof cannot be pried open with the usual burglary tools. Yet, particularly in the case of swingable door panels, when the locking device is in place and in a locked condition, the door panels 10 and 12 have very little significant degree of swinging movement relative to one another. Moreover, no area is presented by which a jimmy or the like can obtain purchase. Hence, it is extremely difficult if not impossible to force the locking device by use of the usual burglary tools.

Although a single embodiment of the invention and incorporation thereof in a pair of panel doors has been disclosed and described in detail, it is obvious that many changes may be made in the size, shape, arrangement and detail of the various elements of the invention, all without departing from the spirit and scope thereof as defined by the appended claims. Thus, while the invention has been described in the context of two panel doors 10 and 12, it is obvious that only one panel door need be involved, and that in place of the other panel door there may be substituted without departing from this invention the adjacent framework such as, for example, a door jamb.

I claim:

1. A locking device for locking a relatively slidable and swingable closure member and the like to an adjacent separate member, both of said members having similarly facing lock sides and similarly facing back sides, said

device comprising a first pin means having a shank for insertion in sliding fit through an aperture in one of said members from one of said sides to the other with a head at one end for positioning on the lock side of said one of said members and at the other end means for engaging fastener element means on the back side of said one of said members, fastener element means for said first pin means, a second pin means having a shank for insertion in sliding fit through an aperture in the other of said members from one of said sides to the other with a head at one end for positioning on the back side of said other of said members and in the region of the other end a transverse peg hole therethrough, latch chain means having an end link at one end mountable on the shank of said first pin means and an end link at the other end mountable on the shank of said second pin means, and fastener means for retaining the corresponding end link of said latch chain means on said shank of said second pin means, said fastener means comprising peg means having a shank for insertion in sliding fit through said peg hole with a head at one end and in the region of the other end an annular recess, and barrel cased lock means engageable in turnable relationship on said shank, said lock means including an inner rotatable lock cam seatable freely in said annular recess whereby to maintain the turnable relationship of said lock means on said shank.

2. A locking device for locking a relatively slidable and swingable closure member and the like to an adjacent separate member, both of said members having similarly facing lock sides and similarly facing back sides, said device comprising a first pin means having a shank for insertion in sliding fit through an aperture in one of said members from one of said sides to the other with a head at one end for positioning on the lock side of said one of said members and at the other end means for engaging fastener element means on the back side of said one of said members, fastener element means for said first pin means, a second pin means having a shank for insertion in sliding fit through an aperture in the other of said members from one of said sides to the other with a head at one end for positioning on the back side of said other of said members and in the region of the other end a transverse peg hole therethrough, latch chain means having an end link at one end mountable on the shank of said first pin means and an end link at the other end mountable on the shank of said second pin means, and fastener means for retaining the corresponding end link of said latch chain means on said shank of said second pin means, said fastener means comprising a peg means having a shank for insertion in sliding fit through said peg hole with a head at one end and in the region of the other end an annular recess, and barrel cased lock means having a barrel casing with a passageway through one end thereof for receiving said peg shank, an open end cylinder lock chamber, a cylinder lock with a revolvable plug in said lock chamber, an interconnecting chamber connecting said passageway and said cylinder lock chamber for accommodating a lock cam on said revolvable plug, an inner lock cam on said revolvable plug seatable freely in said annular recess of said peg shank, and means for holding said cylinder lock in place, each element employed having sufficient free fit with respect to contiguous elements to provide one or both of a sliding and turnable relationship therebetween.

3. A locking device according to claim 2 which includes freely turnable washer means on said first and second pin means adjacent said closure members.
